UNITED STATES PATENT OFFICE.

BERNARD WILLIAM PALIN COGHLIN, OF MONTREAL, QUEBEC, CANADA.

GROUND-ANCHOR.

1,084,695.

Specification of Letters Patent. Patented Jan. 20, 1914.

Application filed December 9, 1910. Serial No. 596,497.

To all whom it may concern:

Be it known that I, BERNARD WILLIAM PALIN COGHLIN, of the city of Montreal, in the Province of Quebec, Canada, manufacturer, have invented certain new and useful Improvements in Ground-Anchors; and I do hereby declare that the following is a full, clear, and exact description of the same.

The invention may be said to consist of 10 the combination and construction of parts hereinafter described and illustrated in the accompanying drawings in which similar reference characters indicate the same parts and wherein—

15 Figure 1 is a side elevation of my improved ground anchor; Fig. 2 is a plan view of the top thereof drawn on a larger scale, the guy being removed; Fig. 3 is a longitudinal sectional view thereof, the head of the 20 rod being shown in elevation; Fig. 4 is a side elevation of the sleeve ready to have the guy connected thereto; and Fig. 5 is a view illustrating the ground anchor when in position to be driven into the ground.

25 Heretofore the driving bar of the anchor was formed with an eye at its upper end and the force of the blows on such end when the latter was being driven into the ground, compressed the eye and made the latter use- 30 less for connecting the guy to the bar. To overcome this I provide a metal sleeve slidably mounted on the bar *c* and provided with eyes *c'* for the guy. The upper portion *d* of this sleeve is of larger diameter 35 than the lower portion *e*, the portion *f* of the hole therein being also of greater diameter than the portion *g* in the lower part which latter portion of the hole is of just sufficient diameter to effect a sliding fit on 40 the bar thus forming midway of the length of the sleeve an internal annular shoulder *h* to be presently further alluded to. At opposite sides of the upper portion of the sleeve are eyes *c'* communicating with the hole *f* and situated a short distance above the shoulder *h*, such eyes receiving the guy *j* which is 45 accommodated in grooves formed in the sleeve and communicating with the eyes *c'*. These grooves are preferably convex as at *k*, 50 and are flared at the top. The end of the bar is upset to present a round driving head *m* of larger diameter than the main length of the bar, and adapted to enter the upper portion of the sleeve, and engage the annular shoulder *h*, thereby transmitting the

strains on the guy to the anchor. When the anchor is to be driven into the ground the sleeve is allowed to slide down the bar *c* (see Fig. 5) the exposed head *m* presents a striking surface for the hammer without exposing the eyes *c'* to damage. After the anchor is driven the guy wire is attached to the sleeve.

Although I have described my invention as applied to ground anchors, it may be applied advantageously to any means requiring to be driven and have guys attached thereto.

What I claim is as follows:—

1. In a ground anchor, the combination with a metal bar having an impact head at one end, of a sleeve swiveled upon the bar and adapted to freely pass to a point below the impact head, said sleeve having eyes therein to receive a guy wire, and an internal shoulder located at a distance from the ends of such sleeve and adapted to be engaged by the impact head to retain the sleeve against displacement from the bar, substantially as described and for the purpose set forth.

2. In a ground anchor, the combination with a metal bar having an impact head at one end, of a sleeve swiveled upon the bar and adapted to freely pass to a point below the impact head, said sleeve comprising a lower portion having a hole therethrough, below and of less diameter than the impact head and completely encircling the bar, and a substantially flat upper portion having diametrically opposite eyes therein and formed with a hole therethrough of greater diameter than the impact head, completely encircling the latter and communicating with the hole of the lower portion and an internal angular shoulder formed by the two holes, at a point below the impact head.

3. In a ground anchor, the combination with a metal bar having an impact head at one end, of a sleeve swiveled upon the bar and adapted to freely pass to a point below the impact head, said sleeve comprising a lower portion having a hole therethrough, below and of less diameter than the impact head and completely encircling the bar, and a substantially flat upper portion having diametrically opposite eyes therein and presenting external grooves extending upwardly and flared outwardly from said eyes and having convexed bottoms, said flat upper portion of the sleeve

having a hole therethrough of greater diameter than the impact head, completely encircling the latter and communicating with the hole of the lower portion, and an internal angular shoulder formed by the two holes, at a point below the impact head.

In testimony whereof, I have signed my

name to this specification, in the presence of two subscribing witnesses.

BERNARD WILLIAM PALIN COGHLIN.
